UNITED STATES PATENT OFFICE.

ADOLPH J. JAHDE, OF CHARTER OAK, IOWA, ASSIGNOR OF ONE-HALF TO HANS F. MAHLSTEDT, OF SCHLESWIG, IOWA.

HOG TROUGH.

Application filed May 2, 1924. Serial No. 710,564.

To all whom it may concern:

Be it known that I, ADOLPH J. JAHDE, a citizen of the United States, and a resident of Charter Oak, in the county of Crawford and State of Iowa, have invented certain new and useful Improvements in Hog Troughs, of which the following is a specification.

My invention relates to watering troughs, particularly for use for watering hogs, and it is my purpose to provide such a trough which is very simple, durable, and inexpensive in construction.

A further object is to provide such a trough, together with means for securing it to a support, whereby the hogs cannot overturn it or push it from place to place.

A still further object is to provide such a trough which is secured to a support in such a manner that it may be rotated around a portion of its supporting means in order to empty water from it.

A still further object is to provide securing mechanism whereby the trough may be entirely detached from its support when desired.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a plan view of my trough secured to a support.

Fig. 2 is a sectional view through the support showing the trough in end elevation.

Fig. 3 is a transverse sectional view, taken on the line 3—3 of Fig. 1.

One of the difficulties experienced with the average hog watering trough is that the hogs will push it from place to place, and the friction with the ground will eventually wear through the bottom of the trough. For this reason it is desirable to secure the trough to a support.

It is also well-known that the average hog trough becomes muddied very quickly by the feet of the hogs, and it is necessary to rinse them quite frequently. My invention contemplates the use of a trough which is fixed to a support in such a manner that by simply withdrawing a hinge pin or shaft

from its receiving loops the trough may be pivoted around another pin as an axis, and will automatically drop to a position where the dirty water will entirely drain therefrom.

In the construction of my trough I have embodied these features in a very simple and novel structure, which I will now describe.

I have used the reference numeral 10 to indicate, generally, a gate, the side of a shed, or the like, which is to form a support for my improved trough. I provide the supporting loop members, A, which are formed of a length of strap metal, bent at their ends into the loops or eyes, 11 and 11^a, which are connected by the web of metal, 12.

The supporting loop members are secured to the support, 10, by means of bolts or screws, or the like, 13.

The trough proper comprises a frame work including the end rings, B, which are bent so as to form the top portion, 14, the bottom portion, 15, which may be slightly curved, as shown, and the rear portions, 16, which are bent toward each other and spaced from each other, as shown. The trough has the back, 17, and the front, 18, which is formed integral therewith, and bent forwardly and upwardly from the lower edge of the back, 17. The front, 18, is curved to fit the members, 15. The end members, 19, may be formed integral with the back, 17, and bent and soldered to the front, 18. The rings, B, are connected by the protecting strips, 20, and the members, 18, 15 and 20, are secured together by means of the rivets, 21. A brace, 22, is fixed to the back, 17, by means of rivets, 23, which extend through the back, 17, the brace, 22 and the loop members, C.

The loop members, C, comprise portions of strap metal, similar to the members, A, and include the connecting webs, 24, and end loops or eyes, 25 and 26, formed thereon.

The eyes, 25 and 26, are designed to register with the eyes, 11 and 11^a, respectively. I provide the pivot rods or pins, 28 and 29, designed to be received through the eyes, 11 and 25, 11^a and 26. Each of the rods has a handle, 29^a, by which the rod may be readily withdrawn. It will be seen that by withdrawing the rod, 28, the trough will be

- allowed to drop to the position shown in dotted lines in Fig. 2. The rivet, 21, will contact with the support and the trough will be held in position where the bottom, 18, is substantially perpendicular. Thus the water will be allowed to drain from the trough and the trough may be readily rinsed by throwing water against it from the side and allowing it to drain out. It will be seen that the trough may be drained instantly by withdrawing the pin, 29, or may be readily removed entirely from its support if it is desirable to store it for a time while not in use.
- 15 The braces, 20, protect the trough from being dented. It will be seen that the hogs can in no way injure the trough by hitting it with their snouts.
- There is no mechanism which can get out 20 of order or which can be injured by the hogs.
- My device is of the simplest construction, yet its utility is obvious considering the necessity for cleaning a trough quickly.
- 25 Some changes may be made in the construction and arrangement of the parts of my invention without departing from the real spirit and purpose of my invention, and it is my intention to cover by my claims, 30 any modified forms of structure or use of mechanical equivalents which may be reasonably included within their scope.
- I claim as my invention:
1. A trough having a back, pairs of hinge 35 loops having integral connecting webs fixed to the back of the trough at the ends there-

of and positioned vertically, pairs of supporting loops having integral connecting webs adapted to be fixed to a vertical support, the supporting loops being spaced to 40 register with the hinge loops on the trough, and removable hinge pins for connecting the registering loops together, whereby the trough may be completely removed from the supporting loops or may be allowed to 45 hinge around the lower hinge pin by removal of the upper pin.

2. In combination with a vertical support, a pair of supporting elements comprising webs of strap metal having their 50 ends rolled to form supporting loops and fastened to the support in spaced vertical position, a trough having a normally vertical back, a forwardly and upwardly inclined forward wall, a pair of hinge elements each comprising hinge loops connected by integral webs, fixed to the back at the ends thereof, the hinge loops being positioned to register with the supporting loops, a removable hinge pin for connecting 55 the upper hinge loops to either the upper or lower supporting loops, and a hinge pin for connecting the lower hinge loops to the lower supporting loops, the parts being so arranged that the trough may pivot around 60 the lower hinge pin by removal of the upper hinge pin.

Signed at Schleswig, in the county of Crawford and State of Iowa, this 21st day of April, 1924.

ADOLPH J. JAHDE.
